(57) **CLAIM**

The ornamental design for climbing gloves, as shown and described.

DESCRIPTION

FIG. 1 is a front elevation view of a first embodiment of the climbing gloves;

FIG. 2 is a front elevation view of a second embodiment of the climbing gloves;

FIG. 3 is a front elevation view of a third embodiment of the climbing gloves;

FIG. 4 is a front elevation view of a fourth embodiment of the climbing gloves;

FIG. 5 is a front elevation view of a fifth embodiment of the climbing gloves;

FIG. 6 is a rear elevation view of the first embodiment of the climbing gloves of FIG. 1;

FIG. 7 is a rear elevation view of the second embodiment of the climbing gloves of FIG. 2;

FIG. 8 is a rear elevation view of the third embodiment of the climbing gloves of FIG. 3;

FIG. 9 is a rear elevation view of the fourth embodiment of the climbing gloves of FIG. 4;

FIG. 10 is a rear elevation view of the fifth embodiment of the climbing gloves of FIG. 5;

FIG. 11 is a first side elevation view of the first embodiment of the climbing gloves of FIG. 1;

FIG. 12 is a first side elevation view of the second embodiment of the climbing gloves of FIG. 2;

FIG. 13 is a first side elevation view of the third embodiment of the climbing gloves of FIG. 3;

FIG. 14 is a first side elevation view of the fourth embodiment of the climbing gloves of FIG. 4;

FIG. 15 is a first side elevation view of the fifth embodiment of the climbing gloves of FIG. 5;

FIG. 16 is a second side elevation view of the first embodiment of the climbing gloves of FIG. 1;

FIG. 17 is a second side elevation view of the second embodiment of the climbing gloves of FIG. 2;

FIG. 18 is a second side elevation view of the third embodiment of the climbing gloves of FIG. 3;

FIG. 19 is a second side elevation view of the fourth embodiment of the climbing gloves of FIG. 4;

FIG. 20 is a second side elevation view of the fifth embodiment of the climbing gloves of FIG. 5;

(Continued)

FIG. 21 is a top plan view of the left hand glove of the first embodiment of climbing gloves of FIG. 1, with the top plan view of the right hand glove of the first embodiment of climbing gloves of FIG. 1 being a mirror image thereof; FIG. 22 is a top plan view of the left hand glove of the second embodiment of climbing gloves of FIG. 2, with the top plan view of the right hand glove of the second embodiment of climbing gloves of FIG. 2 being a mirror image thereof;

FIG. 23 is a top plan view of the left hand glove of the third embodiment of climbing gloves of FIG. 3, with the top plan view of the right hand glove of the third embodiment of climbing gloves of FIG. 3 being a mirror image thereof; FIG. 24 is a top plan view of the left hand glove of the fourth embodiment of climbing gloves of FIG. 4, with the top plan view of the right hand glove of the fourth embodiment of climbing gloves of FIG. 4 being a mirror image thereof;

FIG. 25 is a top plan view of the left hand glove of the fifth embodiment of climbing gloves of FIG. 5, with the top plan view of the right hand glove of the fifth embodiment of climbing gloves of FIG. 5 being a mirror image thereof; FIG. 26 is a bottom plan view of the left hand glove of the first embodiment of climbing gloves of FIG. 1, with the bottom plan view of the right hand glove of the first embodiment of climbing gloves of FIG. 1 being a mirror image thereof;

FIG. 27 is a bottom plan view of the left hand glove of the second embodiment of climbing gloves of FIG. 2, with the bottom plan view of the right hand glove of the second embodiment of climbing gloves of FIG. 2 being a mirror image thereof;

FIG. 28 is a bottom plan view of the left hand glove of the third embodiment of climbing gloves of FIG. 3, with the bottom plan view of the right hand glove of the third embodiment of climbing gloves of FIG. 3 being a mirror image thereof;

FIG. 29 is a bottom plan view of the left hand glove of the fourth embodiment of climbing gloves of FIG. 4, with the bottom plan view of the right hand glove of the fourth embodiment of climbing gloves of FIG. 4 being a mirror image thereof; and,

FIG. 30 is a bottom plan view of the left hand glove of the fifth embodiment of climbing gloves of FIG. 5, with the bottom plan view of the right hand glove of the fifth embodiment of climbing gloves of FIG. 5 being a mirror image thereof.
